TIME SWITCH

Frederick C. Holtz, Springfield, Ill., assignor to
 Sangamo Electric Company, Springfield, Ill., a
 corporation of Illinois

Application February 6, 1933, Serial No. 655,355

23 Claims. (CL 200—39)

The present invention relates to time switches. In one embodiment of my invention herein shown, the device is particularly adapted to function as an electric range timer for automatically turning on the heating element of an electric range at any selected time and for automatically turning off this heating element at a later selected time; and in another embodiment of my invention herein shown, the device is particularly adapted to function as an interval timer for opening or otherwise controlling a particular circuit at the expiration of a definite time interval, which time interval can be accurately predetermined based on comparatively short units of time. While the above embodiments are the preferred constructions and uses of my invention, nevertheless it will be understood that my invention is not limited thereto but can also be embodied in other constructions and used for other purposes.

The actuation of the switch contacts is governed by a control member which is initially moved in one direction into a set position by manual operation. Spring means normally tends to move this control member in the opposite direction, back to a normal position. It is this spring actuated return movement of said control member which actuates the switch contacts at the selected predetermined time or times. This return movement is governed by time controlled tripping or releasing devices which can be given any desired time setting.

One of the objects of the invention is to provide an improved construction of time switch wherein this return motion of said control member occurs in two stages or steps. Assuming the control member to have been manually moved into its set position, the first tripping step occurs at the end of a predetermined time interval and allows the control member to move back part way through its return motion. It is held at this point until the expiration of a second time interval, whereupon the second tripping or releasing device permits said control member to move back through a second stage of its return movement. In the electric range timer embodiment of my invention, this two-step operation is utilized to predetermine the times when the switch goes into the "On" position and goes into the "Off" position; and in the interval timer embodiment of my invention this two-step operation is advantageously utilized by having the first tripping operation respond to relatively large divisions of time and by having the sec-

ond tripping operation respond to relatively small subdivisions of time.

Another object of the invention is to provide an improved arrangement whereby the switch contacts can be manually tripped into closed position in the event that the user should desire to control the circuit by a manual switch at some other point. In the preferred embodiments herein shown, this manual tripping of the switch contacts to closed position is effected by a third stage of return movement of said control member, this third tripping operation being effected manually.

Another object of the invention is to provide an improved time switch of the above general description wherein the time tripping functions can be quickly and easily adjusted to different time intervals from the exterior of the device, and wherein the switch can be quickly and easily tripped in the manual tripping operation, so that the housewife or other user can perform these operations without complication or inconvenience.

Another object of the invention is to provide an improved construction and arrangement of the two time controlled tripping devices and their associated time responsive driving members, relatively to which the tripping devices can be given different time settings.

Other objects and advantages of the invention will appear from the following description of two preferred embodiments of my invention. In the accompanying drawings illustrating such embodiments:—

Figure 1 is a front elevational view of the range timer embodiment of my invention;

Figure 2 is a rear elevational view of the same, with portions broken away;

Figure 3 is a sectional view on an enlarged scale, taken approximately on the plane of the line 3—3 of Figure 1;

Figure 4 is a fragmentary perspective view, with portions broken away;

Figure 5 is a detail view of the control arm, illustrating the pivoted mounting of the latch thereon;

Figures 6, 7, 8 and 9 are diagrams illustrating successive positions of the switch control member and the relations of the switch contacts in each of these positions of said control member;

Figure 10 is a front elevational view of the interval timer embodiment of my invention;

Figure 11 is a front view with the lower portion of the casing or supporting frame broken

away to illustrate the gear train, tripping parts, etc.; and

Figure 12 is a horizontal sectional view on an enlarged scale, looking upwardly as indicated by the line 12-12 of Figure 11.

The main frame structure of the device comprises front and rear frame plates 18 and 19 which are fastened in spaced relation by corner spacing posts 21. A face plate 22 is mounted in spaced relation to the front frame plate 18 by screws 23 which thread into spacing posts 24 rigidly secured to the front frame plate 18. All of the visible indicating parts are associated with this face plate 22, including the clock dial 25, clock hands 26, and the other dials and pointers associated with the tripping apparatus to be later described. A finishing bead 27 extends around the marginal portions of the face plate 22, and when the device is assembled in a casing or is built into an electric range, the enclosing wall extends to this finishing bead 27.

The clock 25, 26 may be of the spring-wound type, electric motor driven type, or of the secondary type, receiving impulses from a master clock or other control source. In the embodiment disclosed, I have illustrated a motor driven type of clock, comprising a self-starting synchronous motor 31, particularly for installations where alternating current is available. This motor 31 may be mounted on the back side of the rear frame plate 19, as shown in Figure 2. The driving train from the electric motor to the clock hands, and such other details of the clock movement, have not been illustrated because the same are old and well known. A second hand 26' (Figure 1) or a second disc 28'' (Figure 10) is preferably provided to indicate whether or not the clock is operating. In the range timer embodiment illustrated in Figures 1-4, a gear 32 transmits timed motion from the clock movement to the tripping parts associated with the switch control member, which tripping parts will be later described.

Referring now to the arrangement of the switch contacts, as illustrated in Figures 2 and 4, the stationary and movable contacts 33 and 34, respectively, are mounted on L-shaped bars 35 and 36. The latter are secured to the outer sides of spaced terminal blocks 37 and 38 composed of insulation, these terminal blocks being secured to an insulating panel 39 which is secured to the back side of the rear frame plate 18. The L-shaped supporting bar 35 for the contact 33 holds said contact in substantially stationary relation, while the L-shaped supporting bar 36 for the bottom contact 34 can be forced or sprung downwardly for separating the contacts. A copper conducting strip 42 aids in carrying current to the movable contact, and a reinforcing bar 43 prevents flexing of the horizontal leg portion of supporting member 36. A strip of insulation 44 is secured to the top side of this horizontal leg, and the cam 45, which actuates the switch, is adapted to contact with this strip of insulation. The conductors of the circuit to be controlled are adapted to be connected to the terminal screws 46 threading into the terminal blocks 37, 38. A rear insulating panel 47 is suitably secured to the back sides of said terminal blocks, for enclosing the rear portion of the switch structure. The conductors 48 of the electric motor 31 may be connected to the terminal screws 46, or, where independent circuit connections for said motor are desired, these conductors, or one of them, may

be extended to a terminal post, or posts, 49, mounted on the rear insulating panel 47.

The cam 45 is oscillated into its different positions by a switch control member designated 51 in its entirety. This control member comprises a shaft 51a, an oscillating arm 51b fixedly secured to said shaft, a latch 51c pivotally mounted on the outer end of said arm, and an actuating knob 51d on the front end of the shaft 51a. The cam 45 is fixedly secured to the rear end of said shaft. The shaft has suitable bearing support in the front and rear frame plates 18, 19, for rotative movement and for axial sliding movement. A target or indicating disc 52 is secured fast to the shaft 51a, the front face of said disc bearing the successive indicia: "Set", "On", "Off"; followed by a red target area designated 53. In the oscillation of the shaft 51a these are presented successively in a sight window 54 provided in the lower portion of the face plate 22.

The arm 51b is secured to the shaft 51a at a point between the two frame plates 18 and 19. Referring to Figures 4 and 5, said arm has a spool-shaped hub portion 57 which is rigidly secured to the shaft 51a, as by pinning or in any other suitable manner, whereby the arm oscillates with the shaft and also moves bodily with the shaft in the axial shifting movement of the latter. A coil spring 58 is confined around the shaft between the hub 57 and the back plate 19. The front end of said spring is extended outwardly and provided with a hooked extremity 58' which hooks over the side edge of the arm 51b. The other end 58'' of said spring bears against the stop pin 59 projecting forwardly from the back plate 19. Said spring acts as a torsion spring, normally tending to swing the switch control assembly 51c, 51b, in a counterclockwise direction (as viewed from the front of the device), and it also serves as a compression spring reacting against the back plate 19 and tending to thrust the control assembly forwardly.

The latch or dog 51c is pivotally mounted for sidewise swinging movement on the outer end of arm 51b, oscillating about a pivot stud or screw 61 which is secured to the arm. The normal position of said latch or dog is with the outer beveled nose portion 51e extending outwardly substantially in prolongation of the arm 51b. As indicated by the dotted line position in Figure 5, said latch can swing in one direction relatively to this normal position, such swinging motion being against the pressure of a coil spring 62. The outer end of said spring passes through an apertured lug 61f on the dog and the other end of the spring is hooked over the side of the arm 51b, the intermediate convolutions of the spring being coiled about the forwardly projecting portion of the hub 57. A stop shoulder 61g projects backwardly from the opposite edge of the dog for engaging the back edge of the arm 51b, this stop preventing swinging motion of the dog in the opposite direction from its normal position, and the action of the spring 62 being such as to normally hold this stop shoulder against the arm 51b.

Figures 6, 7, 8 and 9 diagrammatically illustrate how the switch control member 51 cooperates with three tripping or releasing members 63, 66 and 67 which are grouped substantially concentrically about the rotative axis of the control member 51. The tripping members 63 and 66 are time responsive; in the preferred construction illustrated, they consist of rotating shafts which have geared connection with the clock. Cut in said shafts are notches 63a and 66a, respec-

tively. These two shafts 65 and 66 rotate in the counterclockwise direction indicated, and when the bottom of the notch in one of these shafts arrives at a position substantially tangent to the arc A, the shaft releases the control member 51. The arc A defines the path of movement of the outer extremity of the dog 51c. It will be seen from the foregoing that when the shafts 65 and 66 are in any rotated positions other than with their notches 65a and 66a substantially tangent to the arc A, the control member 51 can be latched behind these shafts, with the dog 51c engaging a solid part of the shaft. Figure 6 illustrates the set position of the control member to which it is moved manually in a clockwise direction, and as the control member passes each of the tripping members 65, 66 and 67 in being swung to this set position, the dog 51c oscillates on its pivot screw 61 in passing each of the tripping members. When the control member is in the position illustrated in Figure 6, with the dog 51c engaging a solid part of the shaft 65, the coil spring 58 is tending to swing said control member back through its return movement in a counterclockwise direction. Therefore, as soon as the notch 65a rotates to a position of tangency, the control member 51 is tripped or released and allowed to swing to the position illustrated in Figure 7, where the dog engages a solid part of the shaft 66. As soon as the notch 66a of this shaft arrives in a position of tangency, the control element is again tripped or released and allowed to continue through a second step of return movement, until the dog strikes the third tripping member 67.

The tripping release between the control member and this third stop 67 is preferably effected by relative endwise movement between the control member and said stop member. In the preferred construction, the stop 67 consists of a short pin rigidly anchored in the front frame plate 18 and projecting rearwardly therefrom, and the control member 51 is tripped from said stop by pressing inwardly on the knob 51b, thereby thrusting the swinging arm and its dog 51c inwardly beyond the end of the pin 67, whereby the latter is cleared and the control arm 51b can continue through a third step of return movement down to its final position illustrated in Figure 9. In other possible alternative constructions, the pin 67 might be arranged for the tripping movement, as by providing a knob on the outer end thereof and arranging said pin for sliding or rotating movement, so as to enable the inner end of the pin to be withdrawn from the path of the dog 51c, or so as to enable a notch in said pin, similar to the notches 65a, 66a, to be slid or rotated into the path of the said dog.

Figures 6 to 9, inclusive illustrate the construction of cam 45 which is used in the range timer embodiment of my invention, from which it will be seen that when the control member is in the position illustrated in Figure 6, the righthand lobe 45a of the cam is holding the switch contacts 33 and 34 separated; when the control element is in the position illustrated in Figure 7, the switch contacts are permitted to engage; when the control element is in the position illustrated in Figure 8, the lefthand lobe 45b of the cam holds the contacts separated; and when the control element is in the position illustrated in Figure 9, the switch contacts are permitted to engage.

The two notched tripping shafts 65 and 66 have suitable bearing support in the front and rear frame plates 18, 19, the notches 65a and 66a in said shafts lying in the plane of the control arm

51b between said frame plates. Mounted on said shafts, and rotatable with respect thereto, are two spur gears 71 and 72. These two gears both mesh with the aforementioned gear 32 which is disposed on the front side of the front frame plate 18. The gear 32 is operatively connected through suitable gearing with the clock movement and, hence, the two spur gears 71 and 72 are both driven continuously at a time controlled speed. Said gears 71 and 72 function as time responsive driving members for driving the shafts 65 and 66.

The driving connection between each of these gears and its respective shaft is a friction slip-page connection, being identical in the case of both shafts. Referring to Figure 3, the shaft 65 is formed with a reduced bearing portion, the front edge of which defines a shoulder 65b projecting from the front frame plate 18. A friction spring 73, in the form of a cupped washer or spider, is confined between said shoulder 65b and the adjacent side of the gear 71. This spring is maintained under continuous pressure so that it functions to transmit a drive from gear 71 to shaft 65 by friction. The shaft 65 is formed with a reduced extension 65c projecting forwardly from the shoulder 65b, and the companion shaft 66 is formed with a like reduced extension. Each of the two gears 71 and 72 has a sleeve 74 rigidly secured to its respective gear and rotatably mounted on this shaft extension. Secured fast to the outer end of the sleeve associated with the gear 71 is a rotating dial or disc 16, and secured to the sleeve associated with the other gear 72 is a like rotating dial 17. As shown in Figure 1, these two dials rotate in circular apertures cut in the face plate 25, and marked on the faces of said dials is suitable time indicia 18', 17'. In a range timer embodiment of my invention, the two dials 16 and 17 are geared to make one complete revolution every twelve hours and, accordingly, in such embodiment, the scale markings 18', 17' represent twelve hours, with minor subdivisions of 15 minutes or less. It will be understood that in other embodiments the geared relation of the dials to the time piece may be arranged for a higher or lower rotative speed, and the dial markings would then be modified accordingly. Fixedly secured to the outer ends of the reduced shaft extensions 65c and 66c are pointers 18 and 17 which cooperate with the dials 16 and 17. Printed on the face plate 25 adjacent to the rotating dials are two datum marks 81 and 82 which cooperate with the pointers 18 and 17 in indicating when the automatic tripping operations will occur, i. e., when the two pointers are aligned with their respective marks 81 and 82, the notches 65a and 66a are in their tangent positions for tripping the control member 51.

A pin 83 is passed through each of the reduced shaft extensions 65c, 66c, and has its ends bearing against a washer 84 mounted in front of each dial 16, 17. This pin and washer arrangement sustains the end thrust of the spring spider 73 tending to thrust each of the gears 71 and 72 outwardly along its respective shaft.

The manual setting of each of the tripping shafts 65 and 66 is effected through separate adjusting knobs 85 and 86, both located in proximity to the setting knob 51d and conveniently accessible from the front of the housing. These adjusting knobs are secured to the outer ends of shafts 65 and 66, respectively, which have bearing support in the front and rear frame plates 18 and 19. Secured to the inner portions of these shafts are spur gears 81 and 82, respectively, which mesh

with spur gears 93 and 94 which are rigidly secured to the shafts 65 and 66, respectively. Rotation of the knob 85 is effective through gears 91 and 93 to adjust the tripping shaft 65 to bring its notch 66a and pointer 78 into any desired angular position, the time responsive driving gear 71 and the associated dial 76 meanwhile remaining substantially stationary during such adjusting operation by reason of the friction slippage connection 78; and adjustment of the other knob 86 is effective through gears 92 and 94 to adjust the other tripping shaft 66 to bring its notch 66a and pointer 79 into any desired angular position, the time responsive driving gear 72 and the associated dial 77 also remaining substantially stationary during this adjusting operation by reason of its friction slippage connection 78.

The operation of the above described embodiment is as follows:—Assuming that the housewife desires to have the particular heating element of the range go on at three o'clock and to go off at six o'clock, she turns the knob 85 to rotate the pointer 78 into registration with the "3" marking on the "On" dial 76, and turns the knob 86 to rotate the pointer 79 into registration with the "6" mark on the "Off" dial 77. With these two time settings established, she thereupon revolves the setting knob 51d to swing the control member 51 to its extreme righthand position, as illustrated in Figure 6. In this position, the switch contacts 33 and 34 are open. During the continued rotation of the gear 71, in response to the operation of the clock movement, the shaft 65 is carried around with said gear through the friction clutch connection 78, and when the "3" mark on the dial 76 and the pointer 78 reach the mark 81, the notch 66a in said shaft is in its tangential position and thereupon the control element 51 is snapped back through the first step of its return movement, into the position illustrated in Figure 7. In this position the switch contacts are closed, thereby closing the circuit of the range. Meanwhile, the shaft 66 has also been rotating with its time responsive driving gear 72, and when the "6" mark on the dial 77, and the pointer 79, come into substantial registry with the stationary mark 82, the notch 66a of said shaft is in its tangential position, and thereupon the control member 51 is permitted to snap through the second step of its return movement, into the position illustrated in Figure 8. In this position, the switch contacts are open. This completes the cycle of automatically closing and opening the circuit at predetermined times. As the control element 51 moves between each of the positions illustrated in Figures 6, 7 and 8, the indicia "Set", "On" and "Off" on the target disc 52 appear successively in the sight window 84 so that the housewife can tell instantly the condition of the time switch.

In the event that she should wish to close the switch contacts 33, 34, and have them remain closed independently of time, it is only necessary for her to press inwardly on the setting knob 51d, which serves to thrust the shaft 51a and arm 51b inwardly in opposition to the pressure of the spring 88, thereby causing the dog 51c to clear the inner end of the fixed stop 67, so that the control element can swing down through the last step of its return movement, into the position illustrated in Figure 9, which permits the switch contacts to close. In this position the red target area 58 appears in the window 84, for indicating that the switch is closed. If the housewife desires to have the switch closed at once, 75 with the device only functioning to automatically

open the switch at the expiration of a given time, she may set only the "Off" dial 77 for this time interval and then turn the setting knob 51d only to the "On" position, with the control member 51 latched behind the shaft 66. At the 5 expiration of this set time interval, the switch will automatically open.

Referring now to the interval timer embodiment illustrated in Figures 10, 11 and 12, this embodiment also has the two rotating tripping 10 shafts 65 and 66, but here these two shafts are permanently geared together in a fixed gear ratio. Rigidly secured to shaft 65 is a large spur gear 95, and rigidly secured to shaft 66 is a small spur pinion 96. The pinion 96 meshes with a relatively 15 larger gear 97 and the latter gear drives a small pinion 98 which meshes with the large spur gear 95. The intermediate gears 97 and 98 are secured fast to an arbor 99, which is journaled in the front and back frame plates 18 and 19. Fixedly 20 secured to the front ends of these shafts 65 and 66 are the two indicating dials 101 and 102. In the embodiment illustrated, the above described gear ratio between said shafts is such that the shaft 66 revolves 12 revolutions to each revolution of the shaft 65. Corresponding to this gear ratio, the markings 101' on the dial 101 represent one hour of time divided into five minute intervals, and the markings 102' on the other dial 102 represent five minutes of time divided into 30 one minute intervals. This enables the time interval to be set for any time up to one hour in one minute gradations, or even smaller. It will be understood that in different embodiments and uses of the invention, the gear ratio and the time 35 intervals may be otherwise arranged, appropriate to that embodiment or use.

Motion is transmitted from the clock movement to the two tripping shafts through a gear 104 which meshes with a gear 105 mounted on the 40 shaft 66. The latter gear 105 constitutes the time responsive driving element for the two shafts, the motion transmitted thereto being such as to cause the shaft 65 to rotate once in an hour and to cause the shaft 66 to rotate once in five minutes, 45 as above described. A friction slippage clutch is interposed between the gear 105 and the shaft 66, this clutch connection also consisting of a spring spider 106 (Fig. 12) similar to the spring spiders 73 of the preceding embodiment. The 50 ends of the spider arms bear against the back side of the gear 105 and the hub of the spider bears against a collar 107 on the shaft 66. This friction slippage connection permits the two shafts to be given their manually adjusted settings, but 55 at other times compels these shafts to rotate in response to the operation of the clock.

Both shafts are set simultaneously by the manipulation of one adjusting knob 111, which is secured to a shaft 112 journaled in the spaced 60 frame plates. A gear 113 secured to this shaft meshes with an idler gear 114, which in turn meshes with the pinion 96, the idler gear being mounted on a suitable spindle or arbor 115 journaled in the frame plates.

The oscillatory control assembly 51 is substantially the same as that previously described, with the exception of the cam 45, which has only a single lobe 45c. The third stop is also provided for the control member, in the form of a pin 70 61, like that previously described, from which the control member can be released by pressing inwardly on the knob 51d. The dials 101 and 102 are designated "2" and "1", respectively, on the face plate of the clock. Corresponding thereto, 75

the target disc 52 bears the successive indicia: "On—2", "On—1", "Off"; followed by the red target area 53.

In the operation of this embodiment, it will be assumed that it is desired to close the circuit through the contacts 33 and 34 and to have this circuit open automatically at a predetermined time interval later on—say 43 minutes. Preparatory thereto, the adjusting knob 511 is turned 10 the proper amount to have the "40" mark on the dial 101 just past the arrowhead marker 81, and to have the "3" mark on the dial 102 in register with the arrowhead marker 82. The setting knob 51d is now rotated in a clockwise direction to 15 swing the control arm 51b to its extreme right-hand position, where it becomes latched behind the shaft 65. The indicia "On—2" now appears in the sight window 54, indicating that the time computation is based on the settings of both dials. 20 As shown in Figure 11, this position of the control member disposes the cam lobe 45c out of engagement with the movable switch element, with the result that the switch contacts are in engagement and the circuit is closed. The dials 101 and 102 25 are rotated in their timed movement in a counter-clockwise direction, back toward their zero positions, and the notches are so related to their dials that when the "O" mark of the dial 101 is approximately in register with the arrowhead 30 pointer 81, the notch 65a will be in tripping position, and, likewise, when the "O" mark on the dial 102 is in register with this arrowhead pointer 82, the notch 65a will be in tripping position. It will therefore be seen that substantially at the expiration 35 of 40 minutes or slightly more, the control member 51 will be tripped through the first notch 65a, thereby swinging back into engagement with the other shaft 66. This still leaves the switch contacts closed because the cam lobe has not engaged the movable switch element. The latter shaft and its dial 102 have meanwhile been rotating 40 at a speed twelve times that of the shaft 65, and when the "O" mark on the latter dial comes into registry with the pointer 82, the notch 65a 45 will arrive in its tangential position, thereby tripping the control member and permitting it to swing down into engagement with the fixed stop 67. This will bring the cam lobe 45c into engagement with the movable switch element, resulting 50 in the opening of the switch contacts.

Should the operator desire to set the device for a short time interval of five minutes or less, this setting is established on the "1" dial, designated 102. For example, if only a 3-minute interval is 55 desired, the "3" on that dial is placed in register with the fixed marker 82. Thereupon, the setting knob 51d is rotated through only the first step of its setting actuation, sufficient to latch the control member in engagement with the shaft 66. At this time the indicia "On—1" on the target disc appears in the window 54, indicating that the time setting is based on the indication of the "1" dial. At the expiration of three minutes, the zero mark on this dial will have returned to 65 the fixed marker 82 and the control element will be tripped for swinging back to its switch opening position in engagement with the stop 67.

Attention is directed to the fact that the use of two tripping shafts for controlling the opening of the switch has a two-fold advantage; first, it enables greater accuracy to be obtained in the automatic tripping operation, and, second, it enables small time intervals to be more accurately established in the setting of the device. Refer- 70 ring to the first of these advantages, the shaft 65

is given a slight lead of operation over the shaft 66 so that for any time setting of more than five minutes, the shaft 65 will be sure to trip the control member before the shaft 66 has arrived in its tripping position. Thus, the first shaft only 5 determines the large gradations of time, and the second shaft determines the short gradations of time. Inasmuch as this second shaft 66 has a 10 rotative speed twelve times as high as the first shaft, a much higher degree of accuracy for the short gradations of time can be had from this second shaft, thereby avoiding the necessity of extremely accurate machining operations and avoiding errors from gear backlash, wear, etc. With regard to the second of these advantages, it 15 will be evident that the large scale division of the second dial 102 into one minute intervals enables the operator conveniently to set the device for accurate time gradations over either long or short 20 intervals.

When the control arm is in its "Off" position, against the stop 67, the "Off" indicia on the target disc appears at the window 54. Likewise, as in the previously described embodiment, when the operator desires to close the switch for a utilization of current independently of time, it is only necessary to press inwardly on the setting 25 knob 51d to cause the control arm to clear the inner end of the stop pin 67, whereupon the control member swings downwardly to the limit of its 30 counterclockwise movement, oscillating the cam lobe 45c out of engagement with the movable switch element and permitting the switch contacts to close. In this position, the red target area 53 appears in the sight window 54, indicating 35 that the switch is closed.

While I have illustrated and described what I regard to be the preferred embodiments of my invention, nevertheless it will be understood that such are merely exemplary and that numerous 40 modifications and rearrangements may be made therein without departing from the essence of the invention.

I claim:

1. In a time switch, the combination of contact apparatus, a control member governing said contact apparatus, said control member adapted to be moved from a normal position to a set position, means normally tending to cause a unidirectional return motion of said control member 45 from said set position back to said normal position, tripping stops disposed at different points in the path of such return movement, time responsive driving means for actuating said tripping stops to release said control member, frictional 50 motion transmitting means between said time responsive driving means and said tripping stops, and means for setting said tripping stops relatively to said time responsive driving means.

2. In a time switch, the combination of contact 60 apparatus, an automatic control member, means responsive to the motion of said control member for governing said contact apparatus, said control member adapted to be moved from a normal position to a set position, means normally tending 65 to cause a return motion of said control member from said set position back to said normal position, tripping shafts operative to control said return motion, said shafts having notches therein movable into releasing positions for releasing said 70 control member, time responsive driving means for moving said shafts, and means for setting said shafts relatively to said time responsive driving means.

3. In a time switch, the combination of contact 75

apparatus, an automatic control member, means responsive to the motion of said member for governing said contact apparatus, said control member adapted to be moved from a normal position to a set position, means normally tending to cause a return motion of said control member from said set position back to said normal position, a plurality of tripping shafts disposed at different points in the path of such return movement for causing such return movement to occur in a plurality of steps, said shafts having notches therein movable into releasing positions for releasing said control member, time responsive driving means for said tripping shafts, frictional means for transmitting motion from said driving means to said shafts, and means for setting said shafts relatively to said time responsive driving means.

4. In a time switch, the combination of contact apparatus, an automatic control member, means responsive to the motion of said control member for governing said contact apparatus, said control member adapted to be moved from a normal position to a set position, means normally tending to cause a return motion of said control member from said set position back to said normal position, a tripping shaft for holding said control member in said set position, a second tripping shaft operative to interrupt the return motion of said control member between said set position and said normal position, said shafts having notches therein movable into releasing positions for releasing said control member, time responsive driving means for rotating said shafts, frictional means for transmitting motion from said time responsive driving means to said shafts, and manually actuated means for setting said shafts in different angular positions relatively to said time responsive driving means.

5. In a time switch, the combination of contact apparatus, an oscillatory control member, means responsive to the motion of said control member for governing said contact apparatus, manually actuated means for oscillating said control member from a normal position to a set position, spring means normally tending to cause a return motion of said control member from said set position back to said normal position, a tripping shaft operative to hold said control member in said set position, a second tripping shaft operative to interrupt said return motion at an intermediate point, said tripping shafts having notches therein rotatable into releasing positions for releasing said control member, time responsive driving means for said shafts, frictional means for transmitting motion from said driving means to said shafts, manually actuated means for angularly setting said tripping shafts relatively to said time responsive driving means, and indicating means for indicating the settings imparted to said shafts.

6. In a time switch, the combination of contact apparatus, a control member governing said contact apparatus, said control member adapted to be moved in one direction to a set position, means normally tending to cause a return motion of said control member from said set position, a first stop member governing said return motion, time responsive means for effecting an automatic release between said first stop member and said control member, a second stop member governing said return motion, and manually actuated means for effecting a release between said second stop member and said control member.

7. In a time switch, the combination of contact apparatus, a control member governing said con-

tact apparatus, said control member adapted to be moved in one direction to a set position, means normally tending to cause a unidirectional return motion of said control member in the opposite direction back from said set position, a first stop member governing said return motion, time responsive means for effecting an automatic release between said first stop member and said control member, means for adjusting the position of said first stop member relatively to said time responsive means, a second stop member governing said return motion, and manually actuated means for effecting a release between said second stop member and said control member.

8. In a time switch, the combination of contact apparatus, a control member governing said contact apparatus, said control member adapted to be moved from a normal position to a set position, means normally tending to cause a return motion of said control member from said set position back to said normal position, a plurality of tripping stops disposed at different points in the path of such return movement for causing the return motion to occur in a plurality of steps, time responsive driving means for actuating said tripping stops to release said control member, means for setting said tripping stops in different tripping positions relatively to said time responsive driving means, another stop member governing said return motion, and manually actuated means for effecting a release between said latter stop member and said control member.

9. In a time switch, the combination of contact apparatus, a control member governing said contact apparatus, said control member being movable in two different planes, a time controlled tripping device operative to govern the motion of said control member in one plane, time responsive driving means for said tripping device, a stop member for governing the motion of said control member, and means for moving said control member in the other plane for effecting release between said stop member and said control member.

10. In a time switch, the combination of contact apparatus, a control member governing said contact apparatus and movable in two different planes, said control member adapted to be moved in one plane from a normal position to a set position, means normally tending to cause a return motion of said control member in said latter plane from said set position back to said normal position, a first stop member governing said return motion, time responsive driving means for said first stop member adapted to actuate the latter into releasing position, means for setting said first stop member relatively to said time responsive driving means, a second stop member governing said return motion, and means for moving said control member in the other plane for effecting a release between said second stop member and said control member.

11. In a time switch, the combination of contact apparatus, a control member governing said contact apparatus comprising a shaft mounted for rotative and shifting movements, said shaft adapted to be rotated from a normal position to a set position, means normally tending to cause a return rotation of said shaft from said set position back to said normal position, a time responsive tripping device operative to control said return rotation, a stop member for interrupting said return rotation, and means for sliding said

shaft for releasing said control member from said stop member.

12. In a time switch, the combination of contact apparatus, a control member governing said contact apparatus, said control member adapted to be moved from a normal position to a set position, means normally tending to cause a return motion of said control member from said set position back to said normal position, a series of stops operative to interrupt said return motion at spaced points, time responsive means for automatically effecting release between said control member and a plurality of said stops, and manually responsive means for manually effecting release between said control member and one of said stops.

13. In a time switch, the combination of contact apparatus, a control member governing said contact apparatus, said control member adapted to have rotative movement from a normal position to a set position, means normally tending to cause a return rotation of said control member from said set position back to said normal position, a plurality of stops operative to interrupt said return rotation at spaced points, time responsive means for automatically effecting release between said control member and one of said stops, and manually responsive means for manually effecting release between said control member and one of said stops.

14. In a time switch, the combination of contact apparatus, control mechanism for said contact apparatus comprising a shaft, an arm on said shaft swinging about the axis of said shaft, a plurality of tripping devices disposed substantially concentrically relatively to said axis and adapted to have substantially continuous motion during the normal operation of the time switch, a dog movably mounted on said arm and adapted to be latched behind said tripping devices when said arm is rotated in one direction, means normally tending to cause rotation of said arm in the opposite direction, and time responsive means for actuating one of said tripping devices.

15. In a time switch, the combination of contact apparatus, a rotatable arm, cam means responsive to the motion of said arm for governing said contact apparatus, a rotatable shaft, a latch member mounted on said arm adapted to have latching engagement with said shaft when said arm is swung to one position, and means normally tending to cause a motion of said arm in a direction in opposition to said latched engagement, said shaft comprising a recessed portion operative upon rotating into a predetermined position to release said arm, time responsive driving means for said shaft, frictional slippage means transmitting motion from said driving means to said shaft, and means for setting said shaft relatively to said time responsive driving means.

16. In a time switch for electric ranges and the like, in combination, separable contact members disposed to control the connection of a heating element of the range to a current source, a control member movable from a normal position to a set position for actuating said contact members from one circuit controlling position to the other, means for biasing said arm from said set position to said normal position in a reverse direction to that in which it is moved to said set position, a first tripping element operative to hold said control member in said set position in which said contact members are separated, tim-

ing means operatively connected to said tripping element for effecting release of said control member to close said contact members at a predetermined time, means for presetting said tripping element, a second tripping element disposed to arrest said control member at an intermediate position in its return to said normal position thereby permitting said contact members to remain in engagement as long as said control member remains in said intermediate position, means for operatively interconnecting said timing means with said second tripping element for effecting release of said control member to open said contact members at a predetermined time, and means for presetting said second tripping element.

17. In a time switch, the combination of contact apparatus, a control member governing said contact apparatus, said control member adapted to be moved from a normal position to a set position, means normally tending to cause a return motion of said control member from said set position back to said normal position, a plurality of tripping devices operative to control said return motion, time responsive driving means for said tripping devices including means for driving said tripping devices at different speeds, and means for setting said tripping devices relatively to said time responsive driving means.

18. In a time switch, the combination of contact apparatus, a control member governing said contact apparatus, said control member adapted to be moved from a normal position to a set position, means normally tending to cause a return motion of said control member from said set position back to said normal position, a plurality of tripping devices operative to control said return motion, time responsive driving means for said tripping devices including means for driving said tripping devices at different speeds, and manually actuated setting means for rotating one of said tripping devices relatively to said time responsive driving means.

19. In a time switch, the combination of contact apparatus, a control member, said control member adapted to be moved from a normal position to a set position, means normally tending to cause a return motion from said set position back to said normal position in a direction opposite to movement to said set position, means responsive to said return motion for causing switching actuation of said contact apparatus at a point intermediate the limits of said return motion and continuously rotating time controlled releasing means adapted to be engaged by said control member and governing said return motion.

20. In a time switch, the combination of contact apparatus, a control member, said control member adapted to be moved from a normal position to a set position, means normally tending to cause a return motion from said set position back to said normal position in a direction opposite to movement to said set position, means responsive to said return motion for causing said contact apparatus to assume a circuit closing condition at one point intermediate the limits of said return motion and for causing said contact apparatus to assume a circuit opening condition at another point intermediate the limits of said return motion, and continuously rotating time controlled releasing means arranged to be engaged directly by said control member for governing said return motion.

21. In a time switch, the combination of con-

- 5 tact apparatus, a control member governing said contact apparatus, said control member adapted to be moved from a normal position to a set position, means normally tending to cause a return motion of said control member from said set position back to said normal position, a continuously rotating first holding device operative to control one part of said return motion, a continuously rotating second holding device operative to control another part of said return motion, each of said holding devices being rotatable into a releasing position, and time responsive means for governing the rotation of said holding devices into their releasing positions.
- 10 15 22. In a time switch, the combination of contact apparatus, a control member governing said contact apparatus, said control member adapted to be moved from a normal position to a set position, means normally tending to cause a return motion of said control member from said set position back to said normal position, a time responsive rotatable driving member having substantially continuous rotation during the normal operation of the time switch, a first holding device operative to control one part of the return motion of said control member, a second holding device operative to control another part of said return motion, mechanism for mechanically transmitting motion from said time responsive
- 20 25

driving member to said first holding device, mechanism for mechanically transmitting motion from said time responsive driving member to said second holding device, each of said holding devices being actuated into releasing position by said time responsive driving member, and setting means for changing the position of one of said holding devices relatively to said time responsive driving member for adjusting the time when said latter holding device is moved into releasing 10 position.

23. In a time switch, the combination of contact apparatus, a control member governing said contact apparatus, said control member adapted to be moved from a normal position to a set 15 position, means normally tending to cause a unidirectional return motion of said control member from said set position back to said normal position, a tripping device operative to control said return motion, a time responsive driving 20 device for actuating said tripping device, an indicating dial rotating with one of said devices, a pointer rotating with the other of said devices and cooperating with said dial, and adjusting means for changing the setting of said tripping device relatively to said time responsive driving device. 25

FREDERICK C. HOLTZ.
